UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed February 2, 1925. Serial No. 6,172.

This invention relates to typographical distributing machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In some machines, such as the commercial Model 9, where matrices may be drawn from several magazines and mixed together in the same line, the distributing mechanism includes a primary distributor which first sorts the matrices according to font, and a plurality of main distributors which thereafter sort the matrices of the individual fonts according to character and restore them to their proper channels in the magazines. With this type of distributing mechanism, the matrices, after font separation, pass down chutes or tubes and enter so-called lower distributor boxes, from which they are fed one at a time to the main distributors under the control of reciprocating pawls or escapements. In order that these pawls or escapements may operate properly with the matrices, the latter are provided in their bottom edges with central notches, which necessarily vary in shape and depth according to the thickness of the individual matrices. Besides adding to the cost of production, such notches in the matrices materially limit the space ordinarily required for the regular font notches and, moreover, seriously weaken the matrices, especially when the latter are formed with other necessary cuts or notches. Furthermore, matrices comprising fonts used on other machines, such as those of the single distributor class, are excluded from use on machines of the multiple distributor class described, since they do not have the required central notches.

Primarily, the present invention is intended to obviate the foregoing difficulties and contemplates certain improvements whereby the distributing mechanism may receive and handle matrices of all fonts whether they have or have not the objection-

able central notches referred to. To this end, the matrices are caused to pass by gravity through the lower distributor boxes and bank up against shoulders arranged to arrest them in the path of a vertically reciprocating finger, which lifts them one at a time directly into the threads of the conveying screws. More specifically, the invention is directed to means for insuring the required cooperation between the matrices and lifting finger in a box of this character; first, by providing the box guide rails with notches which prevent the displacement of an arrested matrix from the path of movement of the lifting finger; and second, by providing the lifting finger in its side face with a recess which permits it to partake of a sidewise movement during its upstroke to increase its purchase on the bottom edge of the matrix being lifted.

In the accompanying drawings, the invention has been shown merely in preferred form and by way of example and as applied to the specific type of distributing mechanism indicated. However, many changes and variations may be made therein and in its mode of application which will still be comprised within its spirit. It is to be understood, therefore, that the invention is not limited to any specific form or embodiment, except in so far as such limitations are specified in the claims.

In the drawings:

Fig. 1 is a side elevation of the improved distributor box, partly broken away;

Fig. 2 is a vertical, transverse section, taken on the line 2-2 of Fig. 1;

Fig. 3 is a fragmentary view, similar to Fig. 1, showing a matrix lifted above the arresting shoulders; and

Fig. 4 is a detail perspective view of a linotype matrix.

The matrices X are released by the primary distributor (not shown) and pass through tubes or chutes arranged in communication with the lower distributor boxes B, through which they are guided and sustained in upright position by the engagement of their projecting ears X¹ with the upper and lower inclined rails B¹, B². Each box is associated with a distributor which comprises the usual longitudinally ribbed or permuted bar C and the set of matrix conveying screws C¹, the arrangement being such that as the matrices are delivered,

one after another, within the range of the screw threads, they will be picked up thereby and advanced horizontally across the rail extensions B^3 , B^4 into engagement with the bar C and thence along the same until finally released above their proper magazine channels. The foregoing parts and their mode of operation, except as hereinafter pointed out, are or may be of any approved 10 construction or as embodied in the commercial Model 9 linotype.

According to the present invention, the box rails B^1 , B^2 are provided with upright shoulders B^5 , B^6 disposed in a vertical 15 plane lying slightly beyond the pick-up ends C^2 of the screw threads and adapted to arrest the individual matrices in that plane by contact with their projecting ears X^1 . A vertically reciprocating finger D is 20 arranged to lift the arrested matrices, one after the other, above the shoulders B^5 , B^6 and directly into the screw threads. As shown in Fig. 1, the finger D is connected to the free end of a yielding lever D^1 25 pivoted at its opposite end to the box, as at B^1 , and connected by an adjustable link member D^2 to an eccentric stud protruding from one of the distributor screws C^1 . Accordingly, the lifting finger is given a complete reciprocation at each rotation of the distributor screw, the finger being guided in its vertical movements by a stationary transverse pin D^3 against which it is held 30 under the tension of a helical spring D^4 . The parts are so timed that when a matrix is arrested by the shoulders B^5 , B^6 , the lifting finger D acts (either immediately or preferably after a slight pause) to raise 35 the matrix above the arresting shoulders 40 into engaging relation to the pick-up ends C^2 of the screw threads, which advance the matrix at once onto the rail extensions B^3 , B^4 and before the finger starts to recede.

In order to insure the proper cooperation 45 of the parts, means are provided to prevent the rearward displacement of the individual matrices when they are arrested by the shoulders B^5 , B^6 . To this end, and in the embodiment shown, the guide rails B^1 , B^2 immediately adjacent said arresting shoulders, are formed with notches B^7 , B^8 wherein the projecting ears X^1 of the matrices engage as the latter reach their arrested position above the lifting finger 50 D , the width of these notches being such as to accommodate the thickest matrix ears. It will now be seen that, before being raised by the lifting finger D , each matrix is caused to drop into the notches B^7 , B^8 , 55 whose rear walls are arranged in such close proximity to the arresting shoulders B^5 , B^6 that the matrix cannot be displaced from the path of movement of the lifting finger, as might otherwise be the case. Hence, in 60 the operation of the parts, the matrices will

be delivered to the distributor screws one at a time in the required manner, whether one or more matrices are passing through the distributor box. It may be well to explain, at this point, that ordinarily, in the use of a matrix lifting finger, some form of pusher device is employed to press the matrices up against the arresting shoulders and hold them there until the lifting finger moves upwardly to detach the leading 75 matrix and raise it into engagement with the screw threads. In the present construction, no such pusher device is employed and only the force of gravity is at work to cause the matrices to bank up against 80 the arresting shoulders. It has been found that such gravitational force cannot be relied upon to hold the matrices up against the shoulders and in engaging relation to the lifting finger, as the matrices have a 85 tendency to rebound away from the shoulders and out of the path of the lifting finger. Moreover, even if the matrices should stand in position to be engaged by the lifting finger, they are apt to be displaced rearwardly and become disengaged from the finger before they are raised into the screw threads, and particularly when the extent of engagement between the lifting finger and the bottom edge of the 95 matrix is quite small, as it usually is. These difficulties, however, as above pointed out, are overcome by the provision of the notches B^7 , B^8 into which each matrix must drop before being acted upon by the lifting finger, and which act upon the arrested matrices to prevent their rearward displacement and confine them within the range of action of the lifting finger.

The proper separation of the matrices is 105 further provided for by the employment of a separator blade E , which is arranged to cooperate with the matrices in the usual way through the central vertical cuts X^2 and serves to prevent the lifting of more 110 than one at a time.

In carrying out the invention, means are also employed for imparting a sidewise movement to the lifting finger D during its upstroke to increase its purchase on the bottom edge of the matrix being lifted. In the present instance, the lifting finger is formed in its rear face with a recess D^5 , which when opposite the transverse pin D^3 permits the spring D^4 to move the finger 115 sidewise the desired extent. Thus, the scant initial purchase of the finger on the bottom of the leading matrix (see Fig. 1) is materially increased before the matrix is carried away by the screws (see Fig. 3). 120 It may be noted, in this connection, that when the finger D is in the position shown in Fig. 1, the relation of recess D^5 to the pin D^3 is such that the sidewise movement 125 of the finger does not take place until the 130

top of the latter rises above the bottom edge of the next or succeeding matrix. Consequently, any danger of the finger catching beneath a succeeding matrix on its upstroke is avoided. This feature of imparting a sidewise movement to the lifting finger, for the purpose mentioned, might also be availed of to good advantage in connection with the ordinary "lift box", if desired.

10 Having thus described my invention, its construction and mode of operation, what I claim and desire to secure by Letters Patent of the United States, is as follows:

15 1. In a typographical distributing mechanism, comprising a distributor bar and a set of matrix conveying screws, the combination of guide means along which the matrices pass by gravity, a reciprocating finger for lifting the matrices successively into the threads of the screws, and means for arresting the matrices in the path of movement of the lifting finger and for restraining them against rearward displacement from said path when thus arrested.

20 25 2. In a typographical distributing mechanism, comprising a distributor bar and a set of matrix conveying screws, the combination of guide means along which the matrices pass by gravity, a reciprocating finger for lifting the matrices successively into the threads of the screws, means for arresting the matrices in the path of movement of said finger, and means to prevent rearward displacement of the matrices when thus arrested.

30 35 3. In a typographical distributing mechanism, comprising a distributor bar and a set of matrix conveying screws, the combination of a distributor box through which the matrices pass by gravity, guide rails therein arranged to support the matrices by their projecting ears, a reciprocating finger for lifting the matrices successively into the threads of the screws, shoulders formed on the guide rails to arrest the matrices by their projecting ears in the path of movement of said finger, and means arranged to engage their projecting ears and prevent rearward displacement of the matrices when thus arrested.

40 45 50 55 4. In a typographical distributing mechanism, comprising a distributor bar and a set of matrix conveying screws, the combination of a distributor box through which the matrices pass by gravity, guide rails therein arranged to support the matrices by their projecting ears, and a reciprocating finger for lifting the matrices successively

into the threads of the screws, the said guide rails being provided with shoulders to arrest the matrices in the path of movement of said finger and being formed adjacent said shoulders with confining notches wherein the projecting ears of the arrested matrices engage.

5. In a typographical distributing mechanism, comprising a distributor bar and a set of matrix conveying screws, the combination of a distributor box through which the matrices pass by gravity, guide rails therein arranged to support the matrices by their projecting ears, a reciprocating finger for lifting the matrices successively into the threads of the screws, and means for arresting the matrices in the path of movement of the lifting finger, the said guide rails being formed with notches to receive and confine the projecting ears of an arrested matrix, for the purpose described.

6. In a typographical distributing mechanism, comprising a distributor bar and a set of matrix conveying screws, the combination of guide means along which the matrices pass by gravity, a reciprocating finger for lifting the matrices successively into the threads of the screws, means to arrest the matrices in the path of movement of said finger, means for restraining them against rearward displacement in their arrested position, and a separator device arranged to cooperate with the arrested matrices so as to prevent the lifting of more than one at a time.

7. In a typographical distributing mechanism, comprising a distributor bar and a set of matrix conveying screws, the combination of a vertically reciprocating finger for lifting the matrices successively into the threads of the screws, and means for guiding the finger in its vertical movements, the said finger being recessed for sidewise movement to increase its purchase on the bottom edge of the matrix being lifted.

8. A distributing mechanism according to claim 1, characterized by the fact that the lifting finger is moved sidewise during its upstroke to increase its purchase on the bottom edge of the matrix being lifted.

9. A distributing mechanism according to claim 3, and including as an additional element a separator device to cooperate with the arrested matrices so as to prevent the lifting of more than one at a time.

In testimony whereof, I have affixed my signature hereto.

DAVID S. KENNEDY.
